COVER FOR A PORTABLE FIRE EXTINGUISHER

Arnold H. Koch, Arlington Heights, Ill., assignor to General Fire Extinguisher Corporation, Northbrook, Ill., a corporation of Delaware

Filed Nov. 3, 1967, Ser. No. 9,263

Term of patent 14 years

Int. Cl. D29—01

U.S. Cl. D16—2

The broken lines are shown for illustrative purposes only.

I claim:

The ornamental design for a cover for a portable fire extinguisher, as shown and described.
